UNITED STATES PATENT OFFICE.

ALWIN H. BECK, OF ROCHESTER, NEW YORK, ASSIGNOR TO HICKOK MFG. COMPANY,
INC., OF ROCHESTER, NEW YORK.

BELT BUCKLE.

Application filed June 11, 1923. Serial No. 644,540.

To all whom it may concern:

Be it known that I, ALWIN H. BECK, a citizen of the United States, and resident of Rochester, in the county of Monroe and State of New York, have invented certain new and useful Improvements in Belt Buckles, of which the following is a specification.

The present invention relates to belt buckles and more particularly to the type in which one end of a belt is connected to a clamping means on a buckle frame so that the tension on the belt tends to hold the clamping member firmly against the free end of the belt. An object of this invention is to provide a clamping member which is so formed that it ordinarily adapts itself to belts of different thicknesses.

To these and other ends, the invention consists of certain parts and combinations of parts, all of which will be hereinafter described: the novel features being pointed out in the appended claims.

In the drawings:

Fig. 1 is a front face view of a buckle constructed in accordance with this invention;

Fig. 2 is a rear face view;

Fig. 3 is an enlarged sectional view through the buckle;

Fig. 4 is a detail view through the anchoring member with the clamping means arranged thereon;

Fig. 5 is an enlarged section on the line 5—5, Fig. 4;

Fig. 6 is a rear face view of another embodiment of the invention;

Fig. 7 is a detail view of the swinging anchoring member and clamping means illustrated in Fig. 6;

Fig. 8 is a section on the line 8—8, Fig. 7;

Fig. 9 is a similar view showing the clamping member shifted to an extreme position; and

Fig. 10 is a section on the line 10—10, Fig. 9.

In the illustrated embodiment of the invention, there is provided a buckle frame, in this instance, in the form of a front plate 1, forming a rear clamping surface curved both longitudinally and transversely. This front plate has side flanges 2 with inwardly turned ribs 3 forming a guide for the free end of the belt. Mounted on the frame is

a combined anchoring and clamping means. The anchoring portion of this means is, in this instance, in the form of a swinging member 4, provided with an eye 5 providing a loop or bail through which one end of the belt is passed to anchor the belt to the buckle. This anchoring member is pivoted at 6 through pintles bearing in sleeves 7 rolled from metal at the ends of the inwardly turned ribs 3.

The clamping means, in this instance, is in the form of a slide 8 movable on a surface 9 on the swinging anchoring member 4 under overhanging guides 10 which are received in grooves 11 formed in opposite sides of the sliding clamp. A pin 12, projecting through the swinging anchoring member 4, enters a groove 13 formed in the under side of the slide 8 and limits the movement of the slide on the swinging anchoring member 4. The guiding means on the bail is at a slight angle to the plane of the anchoring member and the slide is thinner adjacent the pivot of the bail or anchoring member than at the opposite side so that, as the slide moves inwardly on the bail or anchoring member, while the latter is in normal position, it tends to move on the bail or anchoring member toward the rear face of the front plate 1 to clamp the belt against said face. The engaging face of the anchoring member is formed with serrations 8^a. When the slide is in the extreme position shown in Fig. 3, the serrations of the clamping slide will lie on opposite sides of a line such as α which intersects the axis of turning of the anchoring member and is at right angles to the plane γ of said anchoring member 4. In this way the proper engagement of the clamping member with the belt end is insured, as the bail or anchoring member is swung on its pivot and thereafter with increased tension on the belt the tension on the belt will tend to move the slide so as to approach the clamping surface or rear face of the front plate 1. Of course, the amount of movement of this slide depends upon the thickness of the belt. The release of the belt end is effected by swinging the bail or anchoring member on its pivot to carry the clamping member away from the clamping surface on the belt frame.

In the embodiment of the invention shown in Figs. 6 to 10, the bail or belt anchoring

- member 4^a is formed from sheet metal and is bent laterally at 4^b and then inwardly and toward the plane of the anchoring member 4^a at 4^c to provide the guiding surface for the clamping member 8^a, the latter having lugs 8^b at opposite ends bent under the portion 4^c to hold the clamping member on the guiding portion 4^c. Pintles 6^a may be extended from opposite sides of the portion 4^b to turn in the frame of the buckle in the same manner as in the embodiment shown in Figs. 1 to 5, inclusive, the buckle frame parts being, in this embodiment, given the same numbers as similar parts illustrated in Figs. 1 to 5. It will be seen that in this embodiment the clamping member varies in width from one edge to the other and operates on a guiding means which is inclined to take the plane of the anchoring member 4^a. It also has serrations which operate in the same manner as those in Figs. 1 to 5. It will be noted that the faces of the serrations or teeth on the pivot side are more inclined on one side than the other and particularly on the side which is nearest the pivot. This arrangement assists in causing the slide to automatically adapt itself to belts of different thicknesses, as the face with the greater incline will strike the belt first and will shift the slide away from the pivot to adapt the same to the thickness of the belt and after this adjustment has taken

place the other side tends to provide a sharp edge which firmly holds the belt.

What I claim as my invention and desire to secure by Letters Patent is:

1. A buckle comprising a frame having a clamping surface, a clamping member for cooperating with said clamping surface, and an anchoring member pivotally supported on the frame and having the clamping member slidable thereon, said clamping member and anchoring member having surfaces extending throughout the greater portion of the cooperating clamping member transversely of the buckle to support said clamping member substantially throughout its length.

2. A buckle comprising a frame having a clamping surface, an anchoring member pivotally mounted on the frame, and a clamping slide for cooperating with the clamping surface guided on the anchoring member in a line at an angle to the plane of the anchoring member, said slide having a serrated clamping face and having, when it is in extreme position on the anchoring member away from the clamping surface on the frame, portions on opposite sides of a line intersecting the axis of turning of the anchoring member and at right angles to the plane of the anchoring member.

ALWIN H. BECK.
